UNITED STATES PATENT OFFICE.

GEORGE R. WORNER, OF ROCHESTER, NEW YORK, ASSIGNOR TO TAYLOR INSTRUMENT COMPANIES, OF ROCHESTER, NEW YORK, A CORPORATION OF NEW YORK.

ENGRAVING MACHINE.

1,428,280.

Specification of Letters Patent. Patented July 18, 1922.

Application filed August 31, 1920. Serial No. 407,087.

To all whom it may concern:

Be it known that I, GEORGE R. WORNER, a citizen of the United States, residing at Rochester, in the county of Monroe and 5 State of New York, have invented certain new and useful Improvements in Engraving Machines; and I do hereby declare the following to be a full, clear, and exact description of the same, reference being had to the 10 accompanying drawings, forming a part of this specification and to the reference numerals marked thereon.

This invention has to do with engraving machines and relates more particularly to 15 such machines of the type employing a movable tool and a plurality of forms or templets for guiding the movement of the tool, the chief object of the invention being to provide a machine of this character with 20 a practically constructed and compact arranged means for holding a large number of templets in such a manner that they may be quickly and conveniently brought to operating position for guiding the tool. To 25 these and other ends the invention consists in certain improvements and combinations of parts all as will be hereinafter more fully described, the novel features being pointed out in the claims at the end of the specification.

In the drawings:

Figure 1 is a side elevation of an engraving machine partly broken away with the present invention applied thereto.

Figure 2 is a top plan view of the same.

Figure 3 is an enlarged elevation of the templet holding means shown in Figure 1.

Figure 4 is a top plan view of the same.

Figure 5 is a view similar to Figure 3 40 from the opposite side of the machine, however, and partly broken away.

Figure 6 is a section on the line 6^a—6^a of Figure 5.

Figure 7 is a fragmentary sectional view 45 on the line 7^a—7^a of Figure 5.

Similar reference characters throughout the several views indicate the same parts.

The embodiment of the invention herein disclosed by way of illustration of the principles involved and a preferred mode of application thereof, is shown as adapted for use with an engraving machine of the templet copying variety well known in the art and comprising a base 10 on which is a 50 pedestal or column 10^a Figure 1, the top of

which has an overhanging arm 11 on the under side of which is pivotally supported as at 12 a pantographic frame 13, Figure 2, one arm or link 14 of which is elongated and provided with means for holding a 60 copying element or stylus 15 adapted to be moved over the form or templet by means of an adjacent handle 16. The pantographic frame 13 also carries on one of its links a depending bearing 17 in which is rotatably 65 supported a spindle having at its lower end the engraving tool 18, the spindle being provided with a pulley rotated by a belt 19 for rotating the tool. The work is supported on a bed or table 20 which is universally adjustable by means well known in the art and operated by handles such as that shown at 20^a.

For supporting a templet holding means or carrier the machine is provided with an 75 arm 21 to which is preferably secured a bracket 22 having a depending flange 23, Figure 6, provided with an opening in which is carried one end of a shoulder spindle 24 held in the opening with its shoulder 80 against the bracket flange by means of a nut 25. Spindle 24 has at its outer end a head 26 and rotatably supports between its head and the bracket flange the hub 26^a of the main templet carrier or drum 27 85 having a closed side 28 supporting a circumferential flange 29. A plate 30 secured to the circumferential flange as by means of screws 31 closes the other end of the drum to impart an attractive appearance and to 90 serve functions described hereafter.

The circumference of the templet carrier or drum 27 preferably has formed therein a plurality of dove tail slots 32 spaced from each other circumferentially of the drum 95 and extending substantially parallel with its axis, and slidably fitted within these slots for adjustment longitudinally thereof, and so as to be removable therefrom, are a plurality of forms or templets 33 having 100 formed therein in intaglio the characters to be engraved which in the present instance are shown as series of numerals for marking the graduated scale of the dial of an indicating instrument. A plurality of short 105 templets are preferably fitted in each slot and each bearing one character, but of course a single templet bearing one or a plurality of characters may be used in each slot. The templets are preferably secured 110

in adjusted position longitudinally of the slot by means of locking plates 34 sliding in the slots and carrying hand screws 35 adapted to clamp the locking plates and the 5 templets in position in the slot.

The copying stylus in the present instance is adapted for movement over a plane surface and therefore the templets have substantially plane surfaces extending parallel 10 with the axis of the carrier or drum, and it is apparent that each templet or series of templets in the different slots may be selectively brought to position for guiding co-operation with the copying stylus at the top 15 of the drum by rotating the latter on its supporting spindle 24. This rotation in the present instance is conveniently accomplished by grasping the drum itself but of course a suitable handle may be provided 20 for this purpose, as well as an index and scale for indicating the templet in operating position. Means are provided for yieldingly holding drum 27 in its various positions of rotary adjustment, with the selected 25 templet under the stylus, comprising a series of recesses 36 with inclined sides in the end 28 of the drum, one corresponding to each of the templet slots. Co-acting with these recesses is the pointed end 37 of a plunger 38 sliding longitudinally in an opening 39 in bracket flange 23. The plunger point is pressed toward the end 28 of the drum for engagement with slots 36 by means of a leaf 30 spring 40, Figures 5 and 7, supported on the 35 bracket flange by means of a screw 41 and having its end bearing against the outer end of the plunger. Means are provided for raising the spring to remove the pressure on the plunger so that the latter may be 40 forced outwardly by the inclined sides of slots 36 when the drum is rotated, comprising a lever 42 having an end 43 engaging under spring 40, the lever being pivotally supported adjacent its center by trunnions 45 44 rotatably supported in ears 45 on the bracket flange 23. The lever is extended upwardly and outwardly to a convenient position adjacent the copying stylus and is provided with a suitable handle 46 by 50 means of which the drum is conveniently released for rotation to select a templet.

In order to conveniently increase the number or range of templets held by the main carrier or drum 27, there is provided an 55 auxiliary templet carrier or drum contained within the main drum and arranged to bring its circumference substantially tangent with the circumference of the main drum at the top of the latter, the circumferential flange 29 of the main drum being cut away at one of the templet carrying slots 32 thereof to afford access for the stylus to the templets in the inner or auxiliary drum. For this purpose the end 28 of the main 60 drum preferably carries a stud 47 threadedly

engaged therewith, Figure 6, on which is rotatably supported a hub 48 of the auxiliary drum 50 which has a circumferential flange 51 provided with a plurality of dove tail slots 52 similar to those in the main drum 70 and in which are slidably fitted a plurality of templets 53. In the present instance each slot of the auxiliary drum carries a plurality of identical numerals each formed in intaglio, preferably in a separate templet, and 75 the numerals of the ten different slots in successive order about the circumference of the drum comprise the numerals "1" to "9" inclusive, and "0," suitable for engraving on dials, for example, the serial factory 80 numbers of instruments. Other characters of course may be used on templets 53 as occasion may require. Plates 54 are provided to lock the templets in desired position in their slots, the plates being secured 85 in position on the drum as by means of screws 55.

The hub 48 of the auxiliary drum projects through an opening in the end plate 30 of the main drum, Figure 6, and has fixed thereon a finger piece 56 for rotating the drum to select a templet to be brought to copying position, the hub having also fixed thereon a spring finger 57 arranged to engage with a series of depressions 58 formed in the end plate 30 for holding the auxiliary drum in its positions of rotary adjustment. It is apparent from this construction that the inner or auxiliary drum may be rotated to bring its templets selectively to the opening 90 in the main drum and into the locus of the templets of the latter so that when the main drum is positioned with its point of tangency with the auxiliary drum under the stylus, the latter may be brought into co-operation with the templets of the auxiliary drum. As shown in Figure 2 the arm 21 of the machine has secured thereto as by means of screws 59 a guard plate 60 arranged to support the stylus when not in use and also 95 serving as a guard and rest for the hand when moving the stylus over the templet. 100

In operation, with the main and auxiliary drums fitted with templets suitable to the work in hand, such for example as engraving the numerals corresponding to a graduated scale on a dial of an indicating instrument and also the serial number for the instrument, the main drum is rotated to bring the templet or templets carrying the initial numerals to be engraved, say "20," into position for cooperation with the stylus. The work is secured on its supporting bed 20 and adjusted by movement of the bed to bring the tool into proper position relative to the 115 first graduation on the dial to be numbered, and with the tool rotated by its driving means 19, the stylus is then moved to trace the numerals on the templet and the engraving tool engravés corresponding numerals 120 125 130

suitably reduced in size on the work. This operation is repeated for the different numbers to be engraved, as "40," "60," etc., the main drum being rotated to bring 5 such numerals selectively and successively to position for cooperation with the stylus. Similarly when it is desired to engrave the dial with the serial number of the instrument, the main drum is 10 rotated to bring its point of tangency with the auxiliary drum under the stylus and the auxiliary drum is rotated to bring the first or left hand figure forming the serial number to position under the stylus. With the 15 work correspondingly located, the first figure is then traced after which the auxiliary drum is rotated to select the next figure to be engraved and so on until the serial number is completed. The main drum is released 20 for selective rotation by means of the handle 46, and the auxiliary drum is rotated by finger piece 56 and yieldably maintained in adjusted position by spring 57 and recesses 58. While the invention has been 25 explained for purposes of clearness as applied to one specific use, it is obviously capable of use for a variety of engraving work requiring various characters and modifications of the templets.

30 The arrangement of the parts described provides an exceedingly compact and convenient construction for holding a large number of templets in readily accessible condition in a small space. The provision of 35 the inner or auxiliary drum further increases the number and range of available templets occupying a minimum of space, and while but one such inner drum has been shown in the present instance it is to be understood 40 that such auxiliary drum may be duplicated within the main drum if so desired to further multiply its templet carrying capacity.

I claim as my invention:

1. The combination with an engraving 45 machine comprising a tracing element for guiding a tool, of a rotatable templet carrier having a plurality of templets arranged thereon in planes substantially parallel with its rotary axis and adapted to be 50 brought by the rotation of the carrier selectively to position for cooperation with the tracing element.

2. The combination with an engraving 55 machine comprising a tracing element for guiding a tool, of a rotatable drum having on its circumference a plurality of templets adapted to be brought by the rotation of the drum selectively to position for 60 guiding cooperation with the tracing element.

3. The combination with an engraving 65 machine comprising a tracing element for guiding a tool, of a rotatable drum, a plurality of templets on the circumference of said drum, and means for adjustably and re-

movably holding said templets in position to be brought into selective cooperation with said tracing element by the rotation of said drum.

4. The combination with an engraving 70 machine comprising a tracing element for guiding a tool, of a rotatable drum provided on its circumference with a plurality of longitudinally extending slots, a plurality of templets slidably carried in said slots 75 and adapted to be brought selectively to position for cooperation with said tracing element by rotation of said drum, and means for securing said templets in adjusted position in said slots. 80

5. The combination with an engraving machine comprising a tracing element for guiding a tool, of a drum provided on its circumference with a plurality of circumferentially spaced slots, a plurality of templets 85 in said slots, said drum being rotatable to bring said templets selectively to position for guiding cooperation with said tracing element, and means for yieldably holding the drum in its positions of rotary adjust- 90

6. The combination with an engraving machine comprising a movable tool and a tracing stylus having universal movement over a plane surface for guiding the tool, 95 of a drum rotatably carried by said machine, a plurality of templets removably secured on said drum in spaced relation circumferentially thereof and arranged in planes substantially parallel with its axis, 100 said drum being rotatable to bring said templets selectively to position for guiding cooperation with said element, and means for yieldably holding the drum in its positions of rotary adjustment. 105

7. The combination with an engraving machine comprising a tracing element for guiding a tool, of a main templet carrier provided with a plurality of templets and movable to bring said templets selectively 110 to position for cooperation with said tracing element, and an auxiliary templet carrier on said main carrier provided with a plurality of templets and movable to bring its templets selectively into the locus of the 115 templets on said main carrier.

8. The combination with an engraving machine comprising a movable tool and a tracing element for guiding the latter, of a main drum carried by said machine provided with a plurality of templets spaced from each other circumferentially thereof, 120 an auxiliary drum tangentially arranged within said main drum and also provided with a plurality of templets spaced from 125 each other circumferentially thereof, said auxiliary drum being rotatable to bring its templets selectively adjacent the point of tangency with the main drum and said main drum being rotatable to bring its templets 130

and a selected templet of the auxiliary drum selectively to position for cooperation with said tracing element, and means for yieldably holding each drum in its positions of 5 rotary adjustment.

9. The combination with an engraving machine comprising a movable tool and a tracing element for guiding the latter, of a main drum carried by said machine provided with a plurality of templet holding means spaced from each other circumferentially thereof, a plurality of templets removably secured in said means, and an aux-

iliary drum supported within said main drum in substantially tangential relation 15 thereto and also provided with a plurality of templets spaced circumferentially thereof, said auxiliary drum being rotatable to bring its templets selectively into the locus of templets on the main drum and said main 20 drum being rotatable to bring its templets and the selected templet of said auxiliary drum selectively into cooperation with said tracing element.

GEORGE R. WORNER.
